SIDE EXTENSION UNIT FOR A DESK

Douglas C. Ball, Senneville, Quebec, Canada, assignor
to Massey-Ferguson Industries Limited, Toronto, Ontario, Canada

Filed Oct. 7, 1970, Ser. No. 25,371

Term of patent 14 years

Int. Cl. D6—04

U.S. Cl. D6—199

Fig. 1

Fig. 2

Fig. 3

Fig. 4

Fig. 5

FIG. 1 is an elevated right rear perspective view of the side extension unit attachment, showing the tambour bin cover slid open, exposing the storage bin interior.

FIG. 2 is a slightly elevated left side view, showing the bin cover open.

FIG. 3 is a slightly elevated right front perspective view, showing the bin cover open.

FIG. 4 is a plan view, showing the bin cover open.

FIG. 5 is a view similar to FIG. 1, showing the bin cover closed, concealing the storage bin interior.

I claim:

The ornamental design for a side extension unit for a desk, substantially as shown.
